The ornamental design for a crimp fitting for joining tubing as shown and described.

DESCRIPTION

FIG. 1 is a perspective view of a crimp fitting for joining tubing showing our new design;

FIG. 2 is a top view thereof, the bottom view being identical thereto;

FIG. 3 is a cross-sectional view thereof taken about the line 3-3 shown in FIG. 2;

FIG. 4 is an enlarged, partial cross-sectional view taken from detail area 4 of FIG. 3;

FIG. 5 is a right side view thereof, the left view being identical thereto; and

FIG. 6 is a front view thereof, the rear view being identical thereto.

The dot dash broken line indicates cutoff boundaries for enlarged detailed portion views and forms no part of the claim.
